UNITED STATES PATENT OFFICE.

DAVID REYAM, OF WILMINGTON, DELAWARE, AND MOSES MAYER, OF FREEPORT,
NEW YORK.

HOT-AIR RADIATOR.

1,160,761.

Specification of Letters Patent.

Patented Nov. 16, 1915.

Application filed December 14, 1914. Serial No. 877,110.

To all whom it may concern:

Be it known that we, DAVID REYAM, a resident of Wilmington, in the county of New Castle and State of Delaware, and 5 MOSES MAYER, a resident of Freeport, in the county of Nassau and State of New York, both citizens of the United States, have invented a new and Improved Hot-Air Radiator, of which the following is a full, clear, 10 and exact description.

This invention relates to improvements in heating devices and more particularly to a hot air radiator designed to be used in connection with hot air heating systems having 15 a wall pipe for conveying heat from the heating drum of a stove or furnace to the various rooms of the house or building.

An object of the invention is to provide an improved radiator which in general appearance simulates an ordinary steam or hot 20 water radiator but which comprises a novel construction including a plurality of units capable of ready assemblage and equipped with novel means to adapt it for attachment 25 or to be coupled with the register opening in a wall so that the radiator will be made practically continuous with the wall pipe in such a manner as to draw the hot air therefrom, whereas ordinarily the tendency 30 of the hot air to escape through the usual register is at a minimum, thus producing greater heating efficiency.

A further object of the invention is to provide a radiator of the class described 35 which is of the novel construction, the units each being formed of sections of sheet metal and the units necessary to compose a radiator being connected so that all of the units are placed in free communication with each 40 other while permitting the hot air to be deflected into the upper part of each individually, while novel means are provided for regulating the discharge of the hot air from each unit so as to control the heating efficiency 45 of the radiator or the heat radiated therefrom, and also to provide means to avoid any counter-currents of air or preventing the air escaping from the opposite sides of the radiator units near their upper 50 ends from choking or blocking the free escape of the hot air.

With the above and other objects in view, the invention resides in the peculiar combination and arrangement of parts to be hereinafter more fully described, illustrated and

claimed, it being also an object to provide a device which is simple in construction, durable and efficient in operation.

Reference is to be had to the accompanying drawings forming a part of this specification, in which similar characters of reference indicate corresponding parts in all the views, and in which—

Figure 1 is a front elevation of our improved hot air radiator; Fig. 2 is a rear elevation thereof; Fig. 3 is a vertical sectional view taken on the line 3—3 of Fig. 1; Fig. 4 is an enlarged cross sectional view taken on the line 4—4 of Fig. 3; and Fig. 5 is an enlarged horizontal sectional view taken on the line 5—5 of Fig. 2.

In ordinary hot air heating systems employing a furnace with a heating drum or a stove, the heated air passes into and up a wall pipe 10 to be discharged into the various rooms to be heated.

The wall is indicated by the numeral 11 and is provided in each room with a reinforced or lined opening 12 which receives an enlargement 13 constituting a lateral extension of the wall pipe, such being designed to usually receive an ordinary hot air register for controlling or regulating the discharge of the heated air into each room. Owing to the fact that these registers lie 85 flush with the face 14 of the wall of the room, the tendency of the air circulating in the room to create a suction in the wall pipe to draw the heated air therefrom is reduced to a minimum, and this is further 90 the result of the fact that the heated air from the wall pipe must take a lateral path in order to be discharged into the room.

In this manner the heating efficiency of a hot air heating system, employing a stove 95 or furnace, is reduced to a minimum and it is therefore the object of the present invention to overcome these disadvantages by providing a special hot air radiator for use with such heating systems, whereby the 100 proper amount of heat will be drawn from the wall pipe into rooms below the top room supplied with heat through the medium of such a heating system and thereby provide for greater heating efficiency while requiring 105 no special wall structure or modification of the walls as adapted to receive the usual registers. For this purpose a radiator 15 is provided, the same being made up of a plurality of units 16 and each unit preferably 110

comprising sections 17 and 18 of sheet metal, each section being preferably rolled or shaped into concaved form at its surrounding portions, as shown at 19, and the edges 5 of the sections rolled as shown at 20 to provide coating beads, the outer one of which is rolled or clamped over the inner bead to secure the sections together. This is assisted owing to the fact that the beads are 10 curved to an extent greater than 180° and are therefore restricted at the points of juncture of the portions 20 with the curved portions 19 of the sections. The curved portions 19 are convexly arcuate outward so as 15 to provide concaved inner faces, and while one section of each end unit is left rectilinear, one side thereof and the opposed sides of each intermediate unit are formed with apertured outpressed extensions 21 near the 20 upper and lower ends thereof. The sections are held together by means of bolts 22 passing through the horizontally aligned upper and lower series of apertures in the sections of the units at the rectilinear sides of the 25 end units and through the extensions at the inner sides of said units and the opposed sides of the intermediate units, thus providing means to assemble any desired number of units in a radiator, depending upon the 30 size of the room or rooms and the amount of heat required under the particular existing circumstances or the locality and thus the weather conditions.

As heretofore specified, the sections of the 35 units are made up of sheet metal and if desired the end units may be extended to produce legs 23 for supporting the radiator adjacent to the wall. However, if the legs 23 are omitted the radiator may be supported 40 upon a bracket or brackets 24 attached to the baseboard 25 beneath the register opening while the wall and certain units of the radiator have straps or loops 26 attached thereto for engagement by a U-coupling 27 for 45 connecting said parts and holding the radiator at a spaced distance from the wall or in an upright position. In order to place the radiator in communication with the wall pipe, to establish communication of all of 50 the units with each other and adapt the device for register openings of varying sizes, the inner or rear portions of the units are severed or cut out, as shown at 28, and the edges of the recesses thus provided connected by web portions or partitions 29 which close the spaces between the units at the 55 lower portions of the latter to provide an interior space 30 establishing communication with the interior of all of the units. These 60 web portions or partitions produce top walls 31 terminating about midway of the height of the radiator and bottom walls 32 terminating above the loop extensions 21, while the web portions proper, which extend vertically, terminate about midway of the

depth of the radiator units so as to be contiguous with a line connecting the bolts 22, or substantially so. In this manner the units of the radiator will be uniformly heated and aside therefrom will have the remaining areas substantially independently arranged to receive the heated air for independent circulation. The inner side of the casing thus produced is open and at the top and side edges thereof is provided with a 70 slide groove or guideway 33 designed to take a carrying plate 34 vertically from the bottom and in such a manner that the plate will close the back of the casing with the exception of a space produced by a frame 35 projecting therefrom, such frame being designed to enter the register opening, as shown in Fig. 3 of the drawings, so as to place the register in communication with the wall pipe, whereby the hot air passing up 75 the wall pipe will be discharged into the radiators on one or more floors of a house or building.

The function and purpose of removably attaching the plate 34 to the radiator proper 80 is to allow for the construction thereof with projecting frames of varying sizes so that no modification of the heating structure is necessary in order to place the same in communication with the wall pipe where the 85 register openings vary in size. It is to be understood, however, that such plate is made of sufficient size to adapt the radiator to an opening of maximum size so that the device is one of more general application than 90 would otherwise be the case. In this manner communication is established between the radiator as a whole and the wall pipe, as well as with the several units of the radiator, and in order to control the heating 100 efficiency as the hot air escapes into the units of the radiator, the sections of the units or sides thereof which oppose each other, that is, the opposite sides of the intermediate units and the inner sides of the end units, 105 are provided with a plurality of openings 36 arranged in a multiple of rows concentric to the upper connecting bolt 22 as a center, and secured to the sections on the inside are deflector plates 37, one of such 110 plates being provided for each end unit to extend from the outer side thereof and curving upward and across these units to a point slightly above the openings at the opposite sides, while two of such plates are provided 115 at the intermediate ends and diverge upwardly and laterally from the central portions thereof in such a manner as to provide deflectors to discharge the heated air through the openings above mentioned. 120 These deflector plates are of concavo-convex formation and are riveted, bolted or otherwise attached to the sections of the units as shown at 38.

Mounted on the bolts 22 are sleeves 39 130

and also mounted on the upper bolt are valve plates 40, the same being shaped to conform to the interior of the sections of the units with the exception of the outer sides of the 5 end units, and being adapted to turn on the bolt as a pivot. These plates fit in the extensions 21 and are otherwise of substantially semicircular form in plan so as to be capable of rotation within the units to permit 10 the openings 36 to be placed into and out of registration with corresponding openings 41 in the plates. For this purpose each inner section 19 is provided with an arcuate slot 42 through which an extension or lever 15 43 of an adjacent valve plate projects in convenient position to be oscillated for correspondingly moving a valve plate to partly or totally uncover the openings 36 or to entirely close the same as desired, depending 20 upon the amount of heat required. In order to permit the valve plates to be held in adjusted positions the sleeves 39 at their ends engage said plates and are brought into frictional engagement therewith upon the nuts 25 on the extremities of the upper bolt 22 being tightened, and the sleeves additionally serve the dual function of holding said valve plates in adjusted positions against the inner faces of the sections 19 as well as to brace 30 the units and the radiator as a whole.

With the radiator spaced from the wall as shown and described, the air in the room tends to circulate under and upward in back of the same between the radiator and the 35 wall so that a suction or draft is created in the radiator units to draw the heated air from the wall pipe into the radiator through the connection establishing communication between the two. In this manner a greater 40 heating efficiency is produced than with the ordinary register which lies flush with the wall or substantially so, inasmuch as the radiator as a whole forms a section of pipe or box practically making continuous the wall 45 pipe in the room. In this manner it is necessary to provide the regulating or valve plates to control the draft and the discharge of hot air which, owing to the use of the deflector plates or distributors and the arrangement of the openings as specified, will 50 be caused to take effect in such a manner that as it is drawn from each unit or section it will be directed upward. In this manner counter-currents of air or interfering 55 eddies will be avoided by preventing the air from going directly across the spaces between the units which would result in the blocking and choking of the flow of air with obvious disadvantages in the point of heating 60 qualities. To further control the heat radiated, means are provided in the form of a hand operated vertical shaft 44 journaled in the top and bottom portions of the rear extension of the radiator and connected 65 to one of a plurality of pivoted shutters 45

suitably connected as shown at 46 to cause their simultaneous rotation to open or closed positions upon the partial rotation or oscillation of the shaft through the medium of the handle or lever 47 thereof. This handle 70 is preferably disposed near the top of the radiator and being in the space between the radiator and the wall will be out of the way but in convenient position to be operated. It will also be observed that the slots 42 will, 75 through the medium of their end walls, serve to limit the turning movement of oscillation of the valve or controlling plates 40 so that the openings 41 will align with the openings 36 at one limit of the movement of each 80 plate, but will be moved out of alignment with respect thereto to close the openings 36 through the medium of the solid intermediate portions of the plate when oppositely shifted. 85

Having thus described our invention, what we claim as new and desire to secure by Letters Patent is:—

1. The combination with a hot air heating system including the wall pipe and register opening communicating therewith, of a radiator comprising a series of connected units provided on the rear side intermediate of the ends of the units with an extension communicating with each of the said units 90 and fitting in the register opening, and means for controlling the exit of the hot air from each of the units. 95

2. The combination with a hot air heating system including the wall pipe and a register opening communicating therewith; of a radiator comprising a series of connected units having an interior space communicating with all the units and provided with an extension projecting from said space 100 for connection with the register opening to establish communication between the radiator and the wall pipe, means in the extension 105 to control the communication of the register opening with the wall pipe to control the discharge of heat from the wall pipe into the radiator and means at the upper ends of the units to control the operation of the latter independently. 110

3. The combination with a hot air heating system including the wall pipe and a register opening communicating therewith; of a radiator comprising a series of connected units having an interior space communicating with all the units and provided with an extension projecting from said space for connection with the register opening to establish communication between the radiator and the wall pipe, means in the extension to control the communication of the register opening with the wall pipe to control the discharge of heat from the wall pipe into the radiator, said units each having a plurality of openings therethrough and pivoted valve plates having openings adapted to be 115 120 125 130

placed in alinement with the first mentioned openings to permit the passage of heat through the respective units, said plates being designed to be shifted to partly or totally close the openings in the units.

4. The combination with a hot air heating system including the wall pipe and a register opening communicating therewith; of a radiator comprising a series of units placed 10 in communication near their lower portions and provided with an extension for connection with the radiator and the wall pipe, means to control the communication of the register opening with the wall pipe to control the discharge of heat from the wall pipe 15 into the radiator, said units being disposed in spaced relation and having openings in opposed faces thereof near their upper ends, side plates within the units against said faces and having openings therein whereby the first mentioned openings may be covered or uncovered and means to support the radiator at a spaced distance from the wall to permit the circulation of air under and 20 behind the radiator to cause a suction in the units thereof.

5. The combination with a hot air heating system including the wall pipe and a register opening communicating therewith; of a radiator comprising a series of units placed 30 in communication near their lower portions and provided with an extension for connection with the radiator and the wall pipe, means to control the communication of the register opening with the wall pipe to control the discharge of heat from the wall pipe into the radiator, said units being disposed in spaced relation and having openings in 35 opposed faces thereof near their upper ends, side plates within the units against said faces and having openings therein whereby the first mentioned openings may be covered or uncovered and deflector plates within the units designed to deflect the hot air escaping 40 thereinto outwardly and upwardly whereby choking between the units is obviated.

6. A radiator for hot air heating systems comprising a plurality of units, means for connecting said units in spaced relation, means for supporting the radiator through the medium of the units thereof, means to attach the same to a wall opening and the like, distributors at the top portions of the 50 units for deflecting the heated air laterally and upwardly, said units having opposed openings for the escape of said heated air and independently operable means controlling the escape of air through the openings.

7. A radiator for hot air heating systems comprising a plurality of units, means for connecting said units in spaced relation, means for supporting the radiator through the medium of the units thereof, means to attach the same to a wall opening and the 60

like, said connecting means for the units comprising bolts and sleeves mounted on the bolts between the opposed sides of the units, said sides having arcuate series of openings therethrough, plates pivoted to the 70 bolts frictionally engaged by the ends of the sleeves to be held in adjusted position against the inner faces of said sides of the units and having corresponding openings therein and operating members projecting 75 from the plates through the units and adapted for limited movement whereby the plates may be moved into positions for covering and uncovering the openings in the sides of the units.

8. A hot air radiator adapted for use in connection with hot air systems employing a wall pipe and register openings in a wall communicating laterally with respect to said wall pipe, comprising a series of units each 80 formed of a pair of metal sections clamped together, said units having horizontally alined openings through the sections thereof, bolts extending through said openings constituting connecting means for the units, 85 said sections having valve controlled openings therethrough, said units having recesses in their lower portions with partitions therebetween to form a casing placing all of the units in communication and a frame projecting 90 from the casing to fit a register opening.

9. A hot air radiator adapted for use in connection with hot air systems employing a wall pipe and register openings in a wall communicating laterally with respect to said wall pipe, comprising a series of units each 95 formed of a pair of metal sections clamped together, said units having horizontally alined openings through the sections thereof, bolts extending through said openings constituting connecting means for the units, 100 said sections having valve controlled openings therethrough, said units having recesses in their lower portions with partitions therebetween to form a casing placing all of the units in communication, a plate removably carried by the casing and having a projecting frame whereby plates with frames of 105 varying sizes may be provided to fit varying sizes of register openings and valved means controlling communication between the register opening leading from the wall pipe and the interior of the casing communicating 110 with the respective units.

10. A hot air radiator adapted for use in 115 connection with hot air systems employing a wall pipe and register openings in a wall cuminunicating laterally with respect to said wall pipe, comprising a series of units each 120 formed of a pair of sheet metal sections clamped together, said units having horizontally alined openings through the sections thereof, bolts extending through said openings 125 constituting connecting means for the units, said sections having valve controlled 130

openings therethrough, said units having recesses in their lower portions with partitions therebetween to form a casing, said casing being disposed at the inner side of the radiator and having top and bottom walls with the end units closing the ends thereof, a guideway at the top and sides of said casing, a plate removably fitted therein, and having a sleeve to fit a register opening, 5 pivoted shutters controlling the discharge of heated air from the wall pipe into the casing and radiator units and adapted to be operated at the top of the radiator and means to anchor the radiator at a spaced distance 10 from the wall to cause the circulation of air beneath and upwardly in back of the same.

11. A radiator for hot air heating systems comprising a plurality of units each having a pair of sections with their edges rolled to 15 form beads clamped together and rounded adjacent thereto, the end sections of said radiator having rectilinear sides and the intermediate sections having circular extensions contacting to space the sections apart 20 at the opposed faces of the units, said side portions having horizontally alined openings adjacent their upper and lower ends with the openings in the inner sections extending concentrically through the extensions 25 and the end units being extended to produce legs, clamping means extending through the openings and clamping the units together, deflectors in the top portions of the units, the end units each having one deflector 30 extending upwardly and across to the inner side thereof and the other units having diverging deflectors extending from the central portion to the side thereof, said sides having openings adjacent to the extensions, 35 sleeves mounted on the clamping means between the sides of the unit sections, valve plates pivoted on the clamping means between the ends of the sleeves and the inner

faces of said sides and having openings therein, said sides having arcuate slots, levers projecting from the valve plates through the slots whereby the plates may be adjusted to cover or uncover the openings and turned on the pivot and adapted to be frictionally held in adjusted positions, the deflectors serving to cause the escape of the hot air outwardly and upwardly whereby counter-currents between the units is prevented and means placing the units in communication at their rear portions and provided for connection with a hot air conveying passage. 45

12. A hot air radiator, comprising a plurality of connected units having a rear extension intermediate of their ends for connection with a register opening, a plurality 60 of pivoted shutters in the extension, and an operating rod secured to the shutters and extending up at one side of the radiator.

13. A hot air radiator, comprising a plurality of connected units having their inner 65 sides cut out, a casing secured in the cut out portion of the units and having guideways at its edges, and a plate fitting in the said guideways and having at its middle a tubular extension adapted to enter a register 70 opening.
